(57) **CLAIM**

The ornamental design for a wireless charger, as shown and described.

DESCRIPTION

FIG. 1 is a top perspective view of a wireless charger showing my new design;

FIG. 2 is a bottom perspective view thereof;

FIG. 3 is a front elevation view thereof;

FIG. 4 is a rear elevation view thereof;

FIG. 5 is a left side elevation view thereof, the right side elevation view being a mirror image of FIG. 5;

FIG. 6 is a top plan view thereof;

FIG. 7 is a bottom plan view thereof;

FIG. 8 is a top perspective view of the wireless charger in a second state; and,

FIG. 9 is a bottom perspective view of the wireless charger in a second state.

The broken lines in the figures are for the purposes of illustrating portions of the wireless charger, which form no part of the claimed design.

1 Claim, 9 Drawing Sheets
